UNITED STATES PATENT OFFICE.

JAMES MADISON JACKSON, OF PARKERSBURG, WEST VIRGINIA.

BUCKLE.

Application filed July 10, 1924. Serial No. 725,199.

To all whom it may concern:

Be it known that I, JAMES M. JACKSON, of the citizen of the United States, and resident of Parkersburg, in the county of Wood and

5 State of West Virginia, have invented certain new and useful Improvements in Buckles, of which the following is a specification.

My invention is an improvement in buckles 10 or fasteners for the ends of metallic straps, and it consists in the combinations, constructions and arrangements herein described and claimed.

An object of the invention is to provide 15 a fastener of the character described which is simple in construction, reliable in use and thoroughly practical commercially.

A still further object of the invention is to provide a fastener of the character described, which affords facilities for connecting the ends of a metallic strap so that a substantially smooth inner surface will be provided at the juncture of the fastener and the end portions of the straps.

25 Other objects and advantages will be apparent from the following description, considered in conjunction with the accompanying drawings, in which

Figure 1 is a perspective view showing the 30 fastener in use,

Figure 2 is a relatively enlarged section along the line 2—2 of Figure 1, and

35 Figure 3 is a perspective view showing the fastener attached to one end of a metallic strap and the other end portion of the strap moved slightly from position to fully engage with the fastener.

40 Figure 4 is a plan view showing the fastener attached to one end of the strap, the latter being secured to an article which is to be bound thereby,

Figure 5 is a perspective view of the fastener alone.

45 A fastener embodying the invention comprises a substantially flat body 1 which preferably is rectangular in outline and is formed of a thin sheet of material, preferably a light gauge metal. The sheet of metal of which the body is formed is provided with an attaching strip 2 which is merged at its ends into the body 1, as at 3, and has the portion thereof which extends between the end portions 3 offset in respect to the body 1. The attaching strips 2 may 50 be formed by providing parallel slits in the sheet of material and then bending the ma-

terial between the slits laterally of the face of the sheet of material to provide the offset attaching strip 2.

The body 1 also is provided with a second 60 attaching strip 4, which is provided by placing a slot 5 in the sheet of material of which the body is formed, adjacent to the edge of the sheet of material which is opposite the first named edge of the sheet, the slot 5 being disposed in parallel relation to the slits which define the portion of the sheet of material which is subsequently bent or forced laterally to provide the attaching strip 2.

65 The portion of the sheet of material extending between the slot 5 and the adjacent edge of the sheet of material is bent laterally of the same side of the sheet of material as the attaching strip 2 to provide the marginal attaching strip 2 which thus will be offset 70 from the body between its ends which are merged into the body.

75 The offset attaching strips 2 and 4 are substantially equal in length and the length of these attaching strips is slightly greater 80 than the width of the metallic strap 6 with which the fastener is adapted to be used. The metallic strap 6 may be a tie for securing a strip of felt 7 about the leaves of a leaf spring 8 as illustrated in Fig. 1 the 85 strap being secured by suitable fastening devices 9 to the strip of felt at intervals along its length as shown in Figure 4. Manifestly, the use of the strap 6 is not limited to that which is exemplified in Fig- 90 ure 1 but the strap 6 may be suitable for use for binding or tying together articles of various descriptions, as for example a plurality of lengths of lumber or other 95 elongated articles.

95 The strap 6 is made of a metal which is sufficiently flexible and pliable to assume the contour of any article or group of articles about which it is secured. One end of the strap is projected between the attaching strip 2 and the body 1 and then is bent rearwardly over the attaching strip 2 onto the upper face of the body of the strap as indicated at 10, whereby the strap will be attached at one end to the fastener. The strap 105 6 is fashioned at its other end to provide a hook as indicated at 11.

110 From the foregoing description of the various parts of the device, the operation thereof may be readily understood. The metal strap 6 is secured at one end to the attaching strip 2 and is bent about the ar-

title which is to be bound thereby and the body of the fastener is held firmly in a desirable position in respect to the article which is to be bound while the hook-shaped end portion of the strap is pulled to position to overlap the body of the fastener to a distance sufficient to permit the end of the bill of the hook portion 11 to enter the slot 5, whereupon the bill of the hook-shaped portion of the strap will move through the slot 5 across the under face of the attaching strip 4 and will extend slightly beyond the outer edge of the attaching strip 4. Since the attaching strips 2 and 4 are offset in respect to the body 1, it will be manifest that the connected together fastener and strap ends will present a substantially smooth surface and therefore the article or articles which are bound by the strap and fastener will not be marred or injured by any sharp corners or projections. After the strap ends have been disconnected by the fastener in the manner described, the outer or upper surfaces of the connected together portions of the strap ends and the fastener may be made substantially smooth by exerting pressure on the portions of the strap ends which are engaged with the attaching strips 2 and 4, tending to force the latter toward the plane of the body 1. Such pressure on the ex-

posed end portions of the strap also tend to cause the portions of the strap which extend between the attaching strips 2 and 4 and the plane of the body 1 to be clamped between the attaching strips and the body 1 and thus will further secure the strap ends against accidental displacement from engagement with the attaching strips 2 and 4.

Obviously, my invention is susceptible of embodiment in forms other than that illustrated in the accompanying drawings and I therefore consider as my own all such modifications and adaptations of the form of the device herein described as fairly fall within the scope of the appended claim.

I claim:

A fastener of the character described comprising a substantially flat body having a pair of substantially parallel marginal edges, said body having an elongated portion thereof struck laterally therefrom adjacent to one of said marginal edges to provide an elongated attaching strip and having a slot formed therein adjacent to the other of said marginal edges, the portion of the body extending between said slot and the adjacent marginal edge being offset from the same side of the body as said first named attaching strip.

JAMES MADISON JACKSON.
